UNITED STATES PATENT OFFICE.

HENRY RODRIGO, SR., OF HOUSTON, TEXAS.

WELL-SCREEN.

1,256,830.

Specification of Letters Patent. Patented Feb. 19, 1918.

Application filed November 2, 1916. Serial No. 129,138.

To all whom it may concern:

Be it known that I, HENRY RODRIGO, Sr., a citizen of the United States, residing at Houston, in the county of Harris and State 5 of Texas, have invented certain new and useful Improvements in Well-Screens, of which the following is a specification.

This invention relates to new and useful improvements in a well screen.

10 The object of the invention is to provide a screen of the character described particularly adapted to be used in oil or water wells for screening out the sand from the inflowing fluid. When a well is bored it is customary to set a screen composed of one or 15 more joints of perforated pipe therein and the fluid from the surrounding reservoir flows in through the perforations and passes up through the pipe to the surface. The 20 pipe is usually wrapped with spirally wound wire having the turns spaced a small distance apart so as to exclude the sand. Sometimes thimbles with narrow slits are secured in the perforations which act as screens to 25 exclude such sand and other similar detritus. But when a great deal of sand is encountered, the screening surface, however composed, is liable to become clogged by the sand and the inflow of fluid entirely shut 30 off. It is the object of this invention to provide a screen of two concentrically arranged pipes spaced apart and fixed relative to one another, both pipes being perforated and the inner pipe being wrapped with screening 35 wire or provided with screening thimbles or some other similar screening means and the space between the pipes filled with coarse aggregate which intercepts and arrests the sand and detritus and prevents it 40 from reaching this screening surface of the inner pipe and clogging the same.

A further feature of the invention resides in the provision of a screen of the character described which will be simple and inexpensive in its construction and effective in admitting the flow of fluid and excluding the sand and detritus held in suspension therein.

With the above and other objects in view, 50 the invention has particular relation to certain novel features of construction, arrangement of parts and use, an example of which is given in this specification and illustrated in the accompanying drawings wherein:—

55 Figure 1 is a vertical sectional view of the screen.

Fig. 2 is a fragmentary side elevation thereof, and

Fig. 3 shows a plan view of a form of screening thimble employed.

Referring now more particularly to the drawings wherein like numerals of reference designate similar parts in each of the figures, the numerals 1 and 2 refer, respectively, to outer and inner pipe sections concentrically arranged and spaced apart, the pipes being of such a relative diameter as to provide a space 3 between them, usually about one half inch across. These pipes are held in fixed relation by means of the collars 4 and 5 secured upon the inner pipe in any practical manner and to which the outer pipes are also fixed, said collars being spaced a short distance from the corresponding ends of the pipes, and the ends of said pipes which project beyond the respective collars being externally threaded to receive the internally threaded couplings 6 and 7 which are secured thereon and which receive an abutting end of the adjacent section. The ends of the inner couplings abut against the adjacent collars to hold them firmly against the aggregate filled in between them as hereinafter explained. Both outer and inner pipes are perforated, the perforations 8 of the inner pipe being considerably larger in diameter than the perforations 9 of the outer pipe. The inner pipe is wrapped with spirally wound wire 10 of any desirable cross sectional contour, the turns of wire being spaced a distance apart so as to form a narrow spiraled slit between the turns of wire through which the fluid passes to the perforations and thence to the interior of the inner pipe. For the purpose of illustration, the inner pipe shown in Fig. 1 is shown as having also slotted thimbles 11 secured in the perforations, said thimbles taking the place of the spirally wound screening wire, the slits thereof admitting the fluid but excluding the sand. In use, either the spirally wound wire or the thimbles or any other suitable screening surface may be employed.

The space between pipes is filled with a coarse aggregate as gravel, cinder or the like.

As above explained, the perforations of the outer pipe are of small diameter so as to exclude the larger particles of detritus and said outer pipe is not wrapped or provided with a screening surface, as spirally wound wire or slotted thimbles. The inflowing fluid

passes through the perforations 9 of the outer pipe and the sand and detritus held in suspension therein is arrested by the coarse aggregate 12 and does not reach the inner screen in sufficient quantities to clog the same so that the fluid reaches said inner screen comparatively free of detritus and passes through said screen to the interior of the inner pipe and passes through said inner

10 screen up to the surface.

What I claim is:

1. A well screen consisting of an outer and an inner pipe spaced apart, detachable collars interposed between said pipes near their respective ends to secure them in fixed relation to each other, the ends of said pipes being threaded, couplings threaded on said ends, the ends of the inner couplings abutting against the adjacent collars to hold them securely in place, the outer pipe being provided with small perforations and the inner pipe being provided with larger perforations, a

screening surface protecting the perforations of the inner pipe and coarse aggregate filling the space between said pipes and being retained therein by said collars.

2. A well screen consisting of an outer and an inner pipe, detachable collars interposed between said pipes near their respective ends to secure them fixed in spaced 30 relation to each other, each of said pipes being provided with perforations, a screening surface protecting the perforations of the inner pipe, coarse aggregate filling the space between said pipes and being retained there- 35 in by said collars, and means holding said collars in place against said aggregate.

In testimony whereof I have signed my name to this specification in the presence of two subscribing witnesses.

HENRY RODRIGO, SR.
